CLAIM

The ornamental design for a galatians walking liberty cross for jewelry, as shown and described.

DESCRIPTION

This application is related to design patent application Ser. No. 29/800,507, which was filed concurrently on Jul. 21, 2021.

FIG. 1 is a front view of my galatians walking liberty cross for jewelry;

FIG. 2 is a rear view thereof; and

FIG. 3 is a front perspective view thereof; and,

FIG. 4 is a perspective rear view thereof.

The broken lines define the bounds of the claimed design and form no part thereof and the lightened portions of the galatians walking liberty cross for jewelry form no part of the claimed design.

1 Claim, 4 Drawing Sheets
